WILLIAM J. HARTWIG, OF DETROIT, MICHIGAN.

DEVICE FOR TESTING POLE-WINDINGS.

1,345,075.

Specification of Letters Patent. Patented June 29, 1920.

Application filed December 29, 1919. Serial No. 348,086.

To all whom it may concern:

Be it known that I, JASPER F. CULLIN, a citizen of the United States, and residing at Detroit, in the county of Wayne and State of Michigan, have invented a new and Improved Device for Testing Pole-Windings, of which the following is a specification.

This invention consists in simple and effective means for testing the windings of the field coils of motors and dynamos, preferably before these windings are permanently united, and comprises a series of cores on which the windings may be mounted, and a magnetic needle adjacent each core which may be moved to a plurality of indicating positions according to the polarity of the adjacent end of the core when energized by a current in the coil mounted on the core. It also consists in marking opposite poles of adjacent needles so that these markings will indicate correct or incorrect windings of the coils. It further consists in the details of construction illustrated in the accompanying drawing and particularly pointed out in the claims.

In the drawing, Figure 1 is a front elevation of this improved testing machine. Fig. 2 is a plan thereof. Fig. 3 is a section on the line 3—3 of Fig. 2 on a larger scale. Fig. 4 is an elevation of the needles when the poles are properly energized. Fig. 5 is a diagram showing the coils properly connected.

Similar reference characters refer to like parts throughout the several views. This improved testing machine has a base 1 preferably of non-conducting or poor-conducting material, and to it are secured the poles 2, 3, 4, and 5 of soft steel or iron which may easily be impressed with and lose magnetism. Field cores of the electric machines for which the coils are intended may be employed. A small block 45 6 supports one end of the carrier 7, preferably of wood, the other end of which rests on the block 8, being pivoted on the screw 9 and held down by an L-shaped spring clip 10. Any other desired method of mounting this carrier 7 may be employed.

This carrier is formed with chambers 12 and is drilled and tapped to receive the screw-plugs 13 which have conical bearings 14 at their front ends. Across the chambers 55 12 is a narrow bar 15 of metal, secured to

the bar 7 at its ends, and carrying adjustable screws 16, held from turning by jam nuts 17. These screws have conical bearings 18 and in these and in the conical bearings 14 in the plugs 13 are mounted 60 the pintles 19 which support the magnetic needles 21, 22, 23 and 24. Each of these needles is preferably provided with a small counterweight 25 which normally holds it horizontal, and alternate needles have their 65 N arms colored or otherwise marked and the other needles have their S ends thus marked. These needles are normally hidden by the bar 15. Binding posts 27 and 28 are connected to any desired current source 70 by means of wires 29 and 30.

As indicated in Fig. 5, the windings of adjacent field coils are reversed, that is, the windings of the coils 32 and 34 are in the opposite direction from those of coils 33 and 35. These coils are connected by twisting together their ends and are then placed over the pole pieces 2, 3, 4 and 5, the carrier 7 is swung into the position shown in Fig. 1, and the ends of the wires 36 and 37 touched to the posts 27 and 28, when current will pass and the pole pieces will be magnetized, the upper ends of alternate pole pieces being N and of the others S. The carrier 7 is then swung into the position shown in Fig. 1, whereupon the needles will all assume vertical positions, alternate needles having their N poles up. If the coils are all properly placed and connected, the upper 80 ends of the needles will all be marked while the lower ends are plain, or the reverse, as may be predetermined. But if one or all the coils are improperly placed, one or more of the needles will be wrong end up, indicating that one or more of the coils must 85 be turned over or reversed. When all the coils are in proper order, the twisted ends of the windings are soldered together and taped, after which the coils are ready for 90 use.

The details and proportions of this device may all be varied by those skilled in the art without departing from the spirit of my invention as set forth in the following 95 claims.

I claim:

1. In a testing device for coils of electric machines, the combination of a series of cores to hold the coils and means to conduct current to the coils, a magnetic needle ad-

100

105

110

jacent each core, and means to support the needles.

2. In a testing device for coils of electric machines, the combination of a series of 5 vertical cores to hold the coils and means to conduct current to the coils, a normally horizontal magnetic needle adjacent each core, and a horizontal axis for each needle.

3. In a testing device for coils of electric 10 machines, the combination of a series of vertical cores to hold the coils and means to conduct current to the coils, a normally horizontal magnetic needle adjacent each core, and a horizontal axis for each needle,

each of the needles having a counterweight 15 to hold it horizontal until swung from such position by the action of the core when magnetized by the current in the coil.

4. In a testing device for coils of electric machines, the combination of a series of 20 vertical cores to hold the coils and means to conduct current to the coils, a normally horizontal magnetic needle adjacent each core, and a horizontal axis for each needle, one 25 of the arms of each needle having a pre-determined marking, the marked arms of adjacent needles having opposite polarity.

JASPER F. CULLIN.
